UNITED STATES PATENT OFFICE

161,544

AUTOMOBILE RADIATOR GRILLE

Edward O. Sheard, Detroit, Mich., assignor to Chrysler Corporation, Highland Park, Mich., a corporation of Delaware

Application August 13, 1949, Serial No. 4,454

Term of patent 7 years

(Cl. D14—18)

To all whom it may concern:

Be it known that I, Edward O. Sheard, a citizen of the United States, residing in the city of Detroit, county of Wayne and State of Michigan, have invented a new, original, and ornamental Design for an Automobile Radiator Grille, of which the following is a specification, reference being had to the accompanying drawing, forming part thereof, in which:

Fig. 1 is a front elevation of my novel automobile radiator grille;

Fig. 2 is a top plan view thereof;

Fig. 3 is a side elevation of the grille; and

Fig. 4 is a vertical section taken on the line 4—4 of Fig. 1.

I claim:

The ornamental design for an automobile radiator grille, substantially as shown.

EDWARD O. SHEARD.
